UNITED STATES PATENT OFFICE.

JUNICHI KUNIHARA, OF NEW YORK, N. Y.

MATCH ATTACHMENT FOR CIGARETTE OR CIGAR BOXES.

1,119,842.

Specification of Letters Patent.

Patented Dec. 8, 1914.

Application filed April 11, 1914. Serial No. 831,123.

To all whom it may concern:

Be it known that I, JUNICHI KUNIHARA, a subject of the Emperor of Japan, residing in the city, county, and State of New York, have made a certain new and useful Invention in Match Attachments for Cigarette or Cigar Boxes, of which the following is a specification.

This invention relates to that class of boxes in which cigarettes or cigars are usually sold to the retail trade, and particularly to means for equipping such boxes with matches.

The object of my invention is to provide means which are simple and efficient for supplying a match equipment for the box.

A further object of my invention is to utilize the match equipment as a means for preventing the cigarettes or cigars remaining in a partly emptied box from being injured by being jarred against each other or against the sides, ends or cover of the box.

A further object of my invention is to avoid specially constructing a box to hold both cigarettes, etc., and matches, thereby avoiding expense in the manufacture of the box itself.

Other objects of the invention will appear more fully hereinafter.

The invention consists substantially in the construction, combination, location and relative arrangement of parts all as will be more fully hereinafter set forth, as shown in the accompanying drawing, and finally pointed out in the appended claims.

Referring to the appended drawing, Figure 1 is a view in perspective, partly broken, showing an arrangement of the match attachment with respect to the open cigarette box, and embodying my invention. Fig. 2 is a view in section on the line 2, 2, Fig. 1, of the closed box, looking in the direction of the arrows. Fig. 3 is a similar view with the box partially empty showing means for holding the contents in a firm position, and broadly embodying the principles of my invention. Fig. 4 is a view similar to Fig. 2 showing a modified form of attaching the match carrier to the box. Fig. 5 is a similar view showing another form of attachment of the match carrier to the box. Fig. 6 is a view in section taken on the line 6, 6, Fig. 5, and looking in the direction of the arrows.

The same reference numeral designates

the same part wherever it occurs throughout the several figures.

Reference numeral 1 designates a cover hinged to the lower portion 2 of a well known and common form of cigarette or cigar box with contents 12. Attached to the cover is the paper or cardboard folder or carrier 3, carrying the matches 4 in a well known manner. The folder of matches may be of any desired shape and of moderately stiff material, but I have shown the most common form consisting of the matches 4 attached in a suitable manner to the moderately stiff cardboard body of the folder 5, at the base 6 thereof. The folder is formed with a bend 7, and the portion 8, is shown, in the Figs. 1, 2 and 3, as passing through a slit 10 of the box cover and passing back into the interior of the box through a slit 11, terminating in a flap or end portion 9. 75

When the box is purchased, and contains the complete number of cigarettes or cigars to fill the same, the flap portion 9 is in a flat position, as shown in Figs. 1 and 2 against the inner surface of the box top. When, however, the box is partially empty, the flap or end portion 9 is bent under the body 5 of the match carrier as shown in Figs. 3, 4 and 5, thereby serving as a spring to force the matches 4 and the base 6 of the match carried into close contact with the remaining contents 12. This spring effect is sufficient to prevent the movement of the contents and the jarring thereof against each other and against the sides, ends and cover 90 of the box, but it is insufficient to cause damage to the contents due to the pressure exerted thereon.

In Fig. 4 I have shown a modified method of attaching the match folder or carrier 3 95 to the cover 1 of the box. In this form the portion 8 of the folder or carrier is pasted to the under surface of the box cover.

In Figs. 5 and 6, I have shown another arrangement whereby the match folder or carrier is fastened by means of clamps or rivets 13 to the top portion of the box. There are many ways known to those skilled in the art, of attaching the match folder or carrier to the inner surface of the box cover, 105 and it is not my intention to limit the broad scope of my invention to any particular form of said attachment.

In Figs. 5 and 6 I have shown the remaining cigarettes inclosed in the paper wrapper 110

14 in which the cigarettes and cigars are frequently wrapped when placed on sale to the trade. Ordinarily, however, I prefer to interpose a thin sheet 15 between the 5 matches and the cigarettes or cigars. This sheet not only prevents contact of the match heads with the contents of the box but also prevents the closing of the box top from causing the match heads to gouge the box 10 contents.

When a box containing cigarettes becomes partially empty, it is a well known fact that the few remaining cigarettes in the box are jarred by the movements of the person carrying the box, causing the cigarettes to knock against each other and against the 15 top, bottom, sides and ends of the box, causing the tobacco at the ends of the cigarette to become loosened and thereby causing the 20 thus loosened tobacco to either fall out of the cigarette or to be sucked or drawn into the mouth of the smoker when he lights or puffs the cigarette. In the case of cigars, 25 said jarring often causes the cigar wrappers to break. Of course this is undesirable, and my invention, besides furnishing a match supply with the box, also furnishes means to prevent injury to the contents of a partially emptied box from jarring as described 30 above.

The matches employed may be of any suitable or desirable form or type. I prefer to use the so called "safety" match. The sand paper or rough surface along which the match head 4 must be drawn to cause it 35 to ignite, may be provided and placed at any suitable, convenient or familiar point. I have shown at 16, Fig. 6, the application of said sand paper or rough surface portion in 40 such relation as to serve as the hinge of the cover 1 of the box.

Having now set forth the object and nature of my invention and various constructions embodying the principles thereof, what 45 I claim as new and useful and of my own invention and desire to secure by Letters Patent, is:—

1. A cigarette or cigar box comprising a

body portion and a top or cover therefor, in combination with a match carrying 50 folder attached to the inside of the top or cover, and having a foldable flap portion, which, when folded into the space between the body of the folder and the inner surface of the top or cover, serves to yieldingly 55 press the folder against the contents of the box body portion when said top or cover is closed.

2. A cigarette or cigar box comprising a body portion and a top or cover therefor, in 60 combination with a match carrier including a body portion carrying the matches, said body portion being folded to form a securing portion, and a foldable flap portion at the free end of the securing portion adapted 65 to be bent or folded back between the carrier body portion and the securing portion to serve as a yielding means to press the carrier body portion against the contents of the box when its top or cover is closed, means 70 to secure the securing portion to the top or cover, and a sheet interposed between the match carrier and the contents of the box.

3. A cigarette or cigar box comprising a body portion and a top or cover therefor, 75 said top or cover having spaced slits or openings therethrough, in combination with a folder having a body part and a folded portion, said folded portion threaded from the inside of the top or cover through one 80 of said slits and then back through the other of said slits, and terminating in a foldable flap, said body part carrying matches, said flap adapted to be bent or folded back between the body part and inside surface of 85 the top or cover to press the body part against the contents of the box to retain the same from displacement.

In testimony whereof I have hereunto set my hand in the presence of the subscribing 90 witnesses, on this 9th day of April A. D., 1914.

JUNICHI KUNIHARA.
